United States Patent Office

Des. 212,144
Patented Aug. 27, 1968

212,144

RADIOGRAPHIC/FLUOROSCOPIC UNIT

Victor E. De Lucia, Los Angeles, Calif., assignor to Torr
Laboratories, Inc., Los Angeles, Calif., a corporation
of California

Filed Oct. 26, 1967, Ser. No. 9,177

Term of patent 14 years

(Cl. D83—1)

Fig. 3

Fig. 4

FIGURE 1 is a perspective view of a radiographic/fluoroscopic unit taken from the front, to one side and above the unit, showing the new design;

FIGURE 2 is a top plan view of the unit;

FIGURE 3 is a side elevational view of the unit taken from the left-hand side of FIGURE 1;

FIGURE 4 is a side elevational view of the unit taken from the right-hand side of FIGURE 1.

The back of the unit is plain.

I claim:

The ornamental design for a radiographic/fluoroscopic unit, substantially as shown and described.
